UNITED STATES PATENT OFFICE.

WILLIAM P. WILLIAMSON, OF LUDLOW, MASSACHUSETTS, ASSIGNOR TO LUDLOW MANUFACTURING ASSOCIATES, TRUSTEES.

STRAND DETECTOR AND DETAINER.

Application filed July 21, 1926. Serial No. 123,919.

This invention relates to strand detector and detainer mechanism for use with strand or filament handling machinery, such as winding machinery, or textile cordage or 5 wire handling or using machines. A principal object of the invention is to provide a simple, accurate and reliable device adapted to detect either a too thick or too thin place in the strand, wire, cord, yarn, or other filament and to detain the filament when the 10 device has operated to detect such fault.

For these purposes I recommend and shall herein describe effective means for measuring a running filament above and below a required and predetermined diameter, in combination with means acting as a consequence of the occurrence and passage of a fault to cause cessation of continuance of supply of the filament. Assuming use of the invention 20 with machinery causing the filament to run past a point under more or less tension, a preferred form of the device causes cessation of running of the filament by seizing it at or near the fault and permitting it to 25 break; but the invention is adapted for use unchanged with such filament using machinery as may be adapted to stop automatically upon increase in tension of the filament, and in case of such use, the detention of the filament may be resorted to to increase tension 30 rather than to induce breakage.

A device adapted to operate to these effects is particularly useful in connection with winding machines, and especially in 35 connection with winding machines adapted to wind packages for shipment and sale, or for use in textile machinery such as looms, braiding, knitting or netting machines, in which uses it is desirable to prepare the yarn 40 or other cordage by freeing it from obstructions such as slubs or knots, and to make sure that no strand is included in the package for use which varies below a predetermined standard of strength or thickness.

45 In the accompanying drawings selected to illustrate a preferred instance only of mechanism exemplifying the invention,

Fig. 1 is a front elevation;

Fig. 2 is an end elevation from the left 50 of Fig. 1;

Fig. 3 is a section on the line 3—3 of Fig. 1 showing a slab approaching the device which is in open position;

Fig. 4 is a similar section showing the de-

vice in operation to detect and detain a slab; 55 and

Fig. 5 is a similar section showing the device in operation to detect and detain a thin portion.

Referring now to the drawings at an appropriate place on a winding or other yarn, cordage or filament handling machine frame 1, a suitable brace 2 is fixed having a projecting arm 3, forming at its end a cylindrical portion 4 which is bored out to receive 60 a sleeve 5, which is integral with the frusto-conical member 6. This sleeve is held in position by the set screw 7. Positioned through this sleeve is a shaft 8, which is held from withdrawal by cotter pin 9 inserted in one of the spaced holes therein, 10, 10^a, 10^b. Straddled on said sleeve 5 between member 6 and the arm end 4 is an upwardly projecting member 11 split at its 65 bottom and pinched into fixed position over 70 said sleeve by the screw 12.

Opposed to said frusto-conical member 6 is another frusto-conical member 13 loosely mounted on shaft 8 the smaller surfaces 14 and 15 of said members 6 and 13 respectively being adjacent and substantially perpendicular to the axis of shaft 8. Loosely strung on shaft 8 between said members 6 and 13, is a shim 16 of predetermined thickness to separate to the proper distance said 85 surfaces 14 and 15. Said shim 16 may be washer shaped as shown in Figs. 3 and 5 or may be of hairpin shape as in 16^a, Fig. 4, so as to straddle shaft 8. The slope surfaces 17 and 18 of members 6 and 13 respectively may 90 be increased adjacent their smaller surfaces 14, 15 to the slopes 19, 20 respectively in order to define a steeper walled groove for the running of the filament.

The frusto-conical member 13 may be provided with an integral extension 21 surrounding its central bore and adapted to provide a seat for a compression spiral spring 22, seated at its other end on the boss 23, which is permanently fixed to the free 95 end of shaft 8. The member 13 is thus normally pressed against the shim 16 and toward the member 6 but is free to be moved laterally against the compression of the spring 22 for cleaning or for replacing a 100 shim.

For assembly the sleeve 5 of member 6 is slipped into the bore of support 4 and fixed

with set screw 7. The split bottom parts of member 11 are straddled over said sleeve between the support 4 and the large frusto-conical part of member 6, and fixed in nearly upright position by pinch screw 12. There are then threaded on shaft 8, against its boss 23, the spring 22, followed by the member 13 and the shim 16 of desired thickness, and the free end of shaft 8 is projected through the hole in member 6 and its sleeve, against the compression of spring 22 and cotter pin 9 is inserted in the desired hole 10, 10^a, or 10^b, to hold the assembly in position.

15 The members 6 and 13 by the described features thus provide a preferred form of annular V-shaped guide groove communicating at its bottom with a parallel-walled recess between the faces 14 and 15 adapted to 20 be adjusted in width according to the thickness of shim 16.

The member 11 is as aforesaid, straddled over the sleeve 5 of member 6 and pinched into fixed position by the screw 12. The upper end of member 11 is recessed for the reception of a headed stud 24 which may be set and fixed at any adjustment of projection by the set screws 25. Laterally through the head 26 of stud 24 is provided a bore for the 30 reception of a shaft 27 which is fixed by set screw 28 in the top of head 26. The shaft 27 projects laterally over and beyond the center of the guide groove presented by members 6 and 13 and terminates in an enlarged 35 head 29^a. Loosely strung on shaft 27 and bearing against head 29^a is a depending lever 29 with its lower edge 30 accurately positioned over the center of said guide groove, and arcuated eccentrically of its mounting 40 as shown in Figs. 2, 3 and 4. This lower edge 30 is cut away at each side to present a thinner edge portion and is serrated throughout its arc, the teeth of such serration projecting against the direction of movement of the filament, to the left, in Figures 45 3 and 4.

Rigidly secured as by solder to the pivot of lever 29 and loosely strung on shaft 27 against head 26 is a weight 31, the end of 50 which is of considerably greater weight than lever 29. This weight 31 normally projects rearwardly and is set at such angle to lever 29, that when its lower side 32 rests on the larger edge of frusto-conical member 6, the 55 arcuate edge 30 of lever 29 is raised out of the filament guideway presented by members 6 and 13. The degree to which arcuate edge 30 is raised above said guideway is regulated and adjusted by the setting of stud 24 60 in the recess of member 11, as fixed by the set screws 25.

It is desirable that the unit comprising lever 29 and weight 31, be positioned without chance for lateral movement and at the same 65 time be readily movable on shaft 27. This

necessitates smooth bearing surfaces on said unit, on the shaft 27, on its head 29^a and on the side of stud head 26.

Should the thickness of shim 16 be so great as to require lateral adjustment of lever 29 in order that its lower edge 30 be positioned over the center of the guide groove, set screw 28 permits lateral adjustment of the shaft 27 and the unit lever 29 and weight 31 may be held against shaft head 29^a, by the insertion of washers or the like on shaft 27 between the weight 31 and stud head 26. To insure throughout varying adjustments that the rear portion of weight 31 rests on the top of member 6, it will be evident that the bottom 32 of said rear portion should preferably be flat and of considerable width as shown in Fig. 1.

From the above described features it is evident that lever 29 hanging just above the recessed guide groove formed by members 6 and 13, may be adjusted to define a passageway between it and said members 6 and 13 for filaments of less than a predetermined diameter.

In operation the surfaces 14 and 15 of the guide members 6 and 13 are separated by a shim 16 to a predetermined distance which is the distance representing the minimum permissible diameter of the filament *f* with 55 which the device is to be employed. The depending lever 29 is positioned with its lower edge accurately over the center of the recess between members 6 and 13, and adjusted vertically so that in open position (Fig. 3) that point of its arcuate edge 30, nearest the guide passage members 6 and 13 is separated from the lower edges of slopes 19 and 20 on said guide members 6 and 13, by the distance equal to the maximum permissible diameter 100 of said filament.

A convenient method of setting this adjustment is to lay in the guide passageway a metal wire of the diameter of maximum desired filament, rest lever 29 upon said wire 110 with weight 31 seated on the top of member 6, and then fix the set screws 25.

The filament *f* may be slipped down inclined surface 18 of member 13, into the passageway between slopes 19 and 20 and drawn 115 upwardly and along said passageway as indicated, the members being polished so as to offer no resistance over the normally desired tension on the filament.

Whenever the filament *f* falls below the 120 desirable minimum diameter, the stress on the filament causes it to enter the recess between the faces 14 and 15 of the members 6 and 13, there to be wedged and detained resulting in breakage at *a* as illustrated in 125 Fig. 5, or in sufficient tension to operate the stop motion usual to a machine with which the device is to be employed.

Whenever the filament *f* increases to above the desirable maximum diameter, as when a 130

slub or knot occurs thereon as shown at y , Figs. 3 and 4, the too large portion y engages with the projecting teeth on the arcuate edge 30 of lever 29, and swings lever 29 on its pivot and the edge 30 into the passageway as illustrated in Fig. 4, so as to wedge and detain the filament f against the slopes 19, 20 of guide members 6 and 13, resulting as shown in Fig. 4, in breakage at 10 w' or in increased tension to operate a stop motion device. The swinging of lever 29 as its lower edge is swung into the filament passageway lifts weight 31 off its seat on the top of member 6, but immediately upon 15 the clearing of the passageway, weight 31 will resume its seat thereby swinging lever 29 back to open position.

While I have described a preferred form of device exemplifying the new principle of 20 the invention, it will be obvious that other means for measuring the variation of a running filament above and below a required diameter in combination with other means than those described for causing cessation of 25 continuance of supply of the filament past the device as a consequence of the occurrence of a fault would still embody the new idea of means constituting this invention and I am not to be understood as restricting the 30 scope of this invention to the particular devices recommended and herein described.

I claim:

1. Means for detecting improper condition 35 of a running filament comprising in combination means for detecting a thin place adapted and arranged to seize and detain filament having a thin place therein and means reacting with said elements for detaining a filament having a slub.

2. Means for detecting improper condition 40 of a running filament comprising means for detecting a thin place adapted and arranged to seize and detain filament having a thin place therein and means reacting with said elements for detaining a filament having a slub, in combination with means for adjusting the distance apart of the operating surfaces of said means.

3. Means for detecting improper condition 45 of a running filament comprising in combination means for detecting a thin place adapted and arranged to seize and break filament having a thin place therein and means reacting with said elements for detaining a filament having a slub to cause 50 breakage of the filament.

4. Device for detecting imperfection in a 55 filament comprising a guide groove having

therein a recess of measured width for the reception and detention of a too thin part of the filament and a lever disposed within said guide groove so as to normally permit the passage of not too large filament, and means providing an axis perpendicular to the filament passage about which said lever 60 may swing, the lever being constructed and arranged automatically to swing to restrict said filament passage upon the engagement of its lower edge with a too large portion in the filament.

5. Device for detecting imperfection in a filament comprising a base and lever having opposed arcuate surfaces providing between them a passage for a filament of proper size, the base being provided with a recess of 65 measured width for the reception and detention of a too small portion in the filament, and means providing an axis perpendicular to the filament passage about which said lever may swing, the lever being constructed 70 and arranged automatically to swing to restrict said filament passage upon the engagement of its lower edge with a too large portion in the filament.

6. Device for detecting imperfection in a 75 filament comprising a guide groove having therein a recess of measured width for the reception and detention of a too thin part of the filament and a member pivotally disposed within said guide groove so as to normally permit the passage of not too large 80 filament, and provided with a roughened edge portion to engage the surface of a too large part of the filament and eccentrically mounted so as to be pulled by such engagement to restrict said groove whereby to grip 85 and prevent the passage of said too large part.

7. Device for detecting imperfection in a 90 filament comprising a V-shaped guide groove 100 having at its bottom a recess of measured width for the reception and detention of a too thin part of the filament and a member pivotally depending within said guide groove and counterweighted so as to normally permit the passage of not too large 105 filament, and provided with a serrated lower edge portion to engage the surface of a too large part of the filament and eccentrically mounted so as to be pulled by such engagement to restrict said groove whereby to grip 110 and prevent the passage of said too large part.

Signed by me at Ludlow, Massachusetts, this 13th day of July, 1926.

WILLIAM P. WILLIAMSON.
